DESIGN FOR A TOY

Armando Ferrer, Habana, Cuba

Application May 3, 1939, Serial No. 84,774

Term of patent 3½ years

To all whom it may concern:

Be it known that I, Armando Ferrer, a citizen of Cuba, residing at Habana, Cuba, have invented a new, original, and ornamental Design for a Toy, of which the following is a specification, reference being had to the accompanying drawing, forming a part thereof.

In the drawing:

Fig. 1 is a side elevation of a toy embodying my invention.

Fig. 2 is a top plan view of the toy shown in Fig. 1.

Fig. 3 is a cross section on the line 3—3 of Fig. 1, looking in the direction of arrow a.

Fig. 4 is a cross section on the line 3—3 of Fig. 1, looking in the direction of arrow b.

I claim:

The ornamental design for a toy, substantially as shown.

ARMANDO FERRER.
